(57) **CLAIM**

The ornamental design for the concrete form setting and digging hammer, as shown and described.

DESCRIPTION

FIG. 1 is a front perspective view of a concrete form setting and digging hammer, showing my new design;

FIG. 2 is a rear perspective view thereof;

FIG. 3 is a top plan view thereof;

FIG. 4 is a bottom plan view thereof;

FIG. 5 is a left side elevation view thereof;

FIG. 6 is a front elevation view thereof;

FIG. 7 is a rear elevation view thereof;

FIG. 8 is a front perspective view thereof, without the handle;

FIG. 9 is a rear perspective view thereof, without the handle;

FIG. 10 is another top plan view thereof, without the handle; and,

FIG. 11 is another bottom plan view thereof, without the handle.

The broken lines depict portions of the concrete form setting and digging hammer that form no part of the claimed design.
